US0D1027269S

(12) **United States Design Patent** (10) **Patent No.:** **US D1,027,269 S**
(45) **Date of Patent:** **** May 14, 2024**

(54) **LIGHTING FIXTURE**

(71) Applicant: **W Schonbek LLC**, Plattsburgh, NY
(US)

(72) Inventor: **Molly E. McGee**, Tiverton, RI (US)

(73) Assignee: **W SCHONBEK LLC**, Plattsburgh, NY
(US)

(**) Term: **15 Years**

(21) Appl. No.: **29/910,480**

(22) Filed: **Aug. 21, 2023**

Related U.S. Application Data

(63) Continuation of application No. 29/791,169, filed on Jan. 2, 2022, now Pat. No. Des. 1,005,557.

(57) **CLAIM**

The ornamental design for a lighting fixture, as shown and described.

DESCRIPTION

FIG. 1 is a front left perspective view from below of a lighting fixture according to the new design;

FIG. 2 is a front left perspective view from above thereof;

FIG. 3 is a rear right perspective view from above thereof;

FIG. 4 is a rear right perspective view from above thereof;

FIG. 5 is a rear right perspective view from below thereof;

FIG. 6 is a front elevational view thereof;

FIG. 7 is a right side elevational view thereof;

FIG. 8 is a left side elevational view thereof;

FIG. 9 is a rear elevational view thereof;

FIG. 10 is a top view thereof;

FIG. 11 is a bottom view thereof;

FIG. 12 is a front left perspective view from below thereof, but shown illuminated;

FIG. 13 is a front left perspective view from above thereof;

FIG. 14 is a rear right perspective view from above thereof;

FIG. 15 is a rear right perspective view from above thereof;

FIG. 16 is a rear right perspective view from below thereof;

FIG. 17 is a front elevational view thereof;

FIG. 18 is a right side elevational view thereof;

FIG. 19 is a left side elevational view thereof;

FIG. 20 is a rear elevational view thereof;

FIG. 21 is a top view thereof;

FIG. 22 is a bottom view thereof; and,

FIG. 23 is a perspective view from below thereof in a collapsed configuration.

The broken lines in the drawings illustrate portions of the environment and the lighting fixture and form no part of the claimed design.

The stippling shown in FIGS. 12-17 and 20-22 is solely for the purpose of representing the appearance of illumination and does not represent texture or surface ornamentation.

1 Claim, 23 Drawing Sheets
